UNITED STATES PATENT OFFICE

HARRY E. STALEY, OF ROCHESTER, NEW YORK

GARMENT HANGER AND STRETCHER

Application filed October 15, 1928. Serial No. 312,452.

The object of this invention is to provide a new and improved form of hanger for trousers in which the trousers will not only be suspended from the bottom so as to be stretched lengthwise by their own weight, but the bottom of the trousers will be stretched transversely as well.

This and other objects of the invention will be illustrated in the drawing, described in the specification and pointed out in the claim at the end thereof.

In the drawing:

Figure 1 is an elevation of one of my improved hangers.

Figure 2 is a perspective view of one of the spring clamps used in connection therewith.

Figure 3 is an elevation of a modified form of the hanger.

Figure 4 is a detail view of one of the spring clamps used on the hanger shown in Figure 3.

Figure 5 is an elevation of a hanger having a rigid wooden yoke supporting the two separate members of a wire spring yoke.

In the drawings, like reference numerals indicate like parts.

In the drawings, reference numeral 1 indicates the garment hanger made of wire having a hook 2 and a yoke 3 which yoke comprises an upper member 4 and a lower member 5 all of which is made from a single piece of wire bent on itself, the wires being twisted together between the hook and the yoke as is indicated at 6. The lower member 5 of the yoke is shaped so that the two sides thereof slope from the middle down and out. On this lower member are fastened the spring clamps 7 and 8. These clamps have an eye 9 at the top thereof which is inclined with reference to the upright member of the clamp, the inclination being substantially the same as the inclination of either side of the member 5 of the yoke, so that the clamp will hang straight down instead of being inclined side ways as it would be if the eye extended straight across the upright.

In practice the spring clamp 7 will be opened and attached to the bottom of the trousers 10 as indicated at Figure 1 and the

trousers will be suspended therefrom. The clamps will naturally gravitate down and out as they swing on the member 5 and in so doing they stretch the bottom of the trousers transversely and this helps to keep the trousers in better shape. This lateral tension on the bottom of the trousers can be increased by springing the opposite ends of the hanger together to some extent before attaching both of the clamps 7 and 8 to the trousers, and when the ends of the garment hangers are released after the clamps are attached the ends of the yoke will swing back to normal position springing apart as they do this and this will further increase the tension on the bottom of the trousers so that either by the gravity effect on the clamp 7 and 8 due to the shape of the lower member 5 of the hanger which causes the clamps to move apart under the weight of the trousers or because of the spring effect in the yoke or because of both of these features the trousers will be stretched at the bottom, and thus held in proper shape.

In Figure 3 I have shown a hanger having a hook 12 and a yoke 13 made with the inclined members 14 and 15 which are twisted together immediately under the hook. On this yoke 13 is suspended the swinging members 16 and 17, each of which has two clamps thereon for the purpose of hanging two pair of trousers. The members 14 and 15 of the yoke 13 are inclined down and out from the middle in this form so that the clamps 16 and 17 naturally move out as they are pulled down by the weight of the trousers held up thereby. The ends of the yoke 14 and 15 can be sprung together and held in this position while the trousers are attached to the members 16 and 17 and when the ends are released the spring of the yoke will draw or help to draw the bottom of the trousers to shape.

The outer end of the members 24 engages loosely in a large opening in the outer end of the wooden yoke so that it can move up and down freely therein as the member 24 springs at its outer end. This engagement holds the member 24 in line with the wooden yoke and prevents it from swinging on its inner end. The outer end of the member 25 is turned down and curled under as shown. In

both cases the outer ends of the members 24 and 25 are finished so as to hold the members 26 and 27 from falling off.

I claim:

- 5 A garment hanger formed of a single piece of wire, the upper portion of which is shaped to support a coat, the lower portion having two inclined members therein sloping down and out from the center, a spring clamp mounted to slide on each inclined member, the clamps being adapted to hold and hang up trousers by the bottom, the clamps and inclined members being so related that the weight of the
- 10 trousers hanging from the clamps will tend to make the clamps slide down and out on the inclined members and separate the clamps from each other and draw the garment between the clamps out tight and straight, the hanger as a whole being adapted to be sprung in at the ends to facilitate the sliding of the clamps down and out, the ends of the hanger when released being adapted to spring out and help stretch the garment supported between the clamps.
